Primary Examiner — Joseph Kukella(74) *Attorney, Agent, or Firm* — Stoel Rives LLP(57) **CLAIM**

The ornamental design for a rocker chair, as shown and described.

DESCRIPTION

FIG. 1 is a top perspective view of a rocker chair showing the new design;

FIG. 2 is a bottom perspective view thereof;

FIG. 3 is a front view thereof;

FIG. 4 is a rear view thereof;

FIG. 5 is a right side view thereof, the left side view being a mirror image;

FIG. 6 is a top view thereof; and,

FIG. 7 is a bottom view thereof.

The broken lines in the figures depict portions of the rocker chair that form no part of the claimed design.
